P. O. MELAAS

HEATER FOR AUTOMOBILES

Filed July 29, 1922

Patented Dec. 15, 1925.

UNITED STATES PATENT OFFICE.

PALMER O. MELAAS, OF FERGUS FALLS, MINNESOTA.

HEATER FOR AUTOMOBILES.

Application filed July 29, 1922. Serial No. 578,400.

To all whom it may concern:

Be it known that I, PALMER O. MELAAS, a citizen of the United States, residing at Fergus Falls, in the county of Otter Tail and State of Minnesota, have invented certain new and useful Improvements in a Heater for Automobiles, of which the following is a specification.

My invention relates to a heater for automobiles.

An object of my invention is to provide a heater for automobiles, that will utilize heat from the exhaust pipes of an internal combustion engine, to preheat the intake mixture.

A further object of my invention is to provide an attachment for automobiles, which may be used as a heater in cold weather.

A still further object of my invention is to provide a heater for automobiles, that may be readily mounted on any well known form of internal combustion engine, and which may readily be detached when it is desired.

A still further object of my invention is to provide a heater, for automobiles, which may be formed from a single strip of material.

A still further object of my invention is to provide a heater for automobiles, which is strong, durable, simple and inexpensive in construction, and which is well adapted to the use for which it is designed.

Other objects and advantages of the invention will become apparent during the course of the following description.

In the accompanying drawings, forming a part of the specification and in which like numerals are employed to designate like parts through the same,

Figure 1 is a perspective view illustrating my invention applied to an internal combustion engine.

Figure 2 is a top plan view of the strip of material from which my invention is formed.

Figure 3 is a fragmentary longitudinal section through an automobile showing the heater applied thereto, the heater being also shown in section.

Figure 4 is a detail transverse section taken on the line 4-4 of Figure 3, looking in the direction of the arrows, and

Figure 5 is a detail section taken on the line 5-5 of Figure 3 looking in the direction of the arrows.

In the drawings, wherein for the purpose of illustration is shown a preferred embodiment of my invention, the numeral 5 represents any well known form or type of internal combustion engine, as is ordinarily used in an automobile. The numeral 6 represents the carburetor having the intake manifold 7 and the air pipe 8. The strip of material from which my invention is formed, is designated by the numeral 9 in its entirety. Formed in the plate 9 are large openings 10 for the branches of the exhaust manifold to pass through. The smaller openings 11 are formed for the bolts in the motor to pass through to hold the same securely in place when in use. The openings 12 around the outer edge of the plate 9 are made to allow bolts to be passed through the same, to hold the same when it is bent into shape as is illustrated in Figure 1. Irregular portions 13 are cut out of the strip as is illustrated in Figure 2 to allow the pipe 8 to pass through my heater, as is clearly shown in Figure 1 at point 14.

When the strip 9 is formed as is shown in Figure 1, an opening 15 is formed by reason of the cutout portions 16 shown in Figure 2. This opening 15 is opened or closed by means of a valve member 17, said valve member 17 being provided with the arms 18 which protrude through the openings 19. Any form of control mechanism may be attached to one of the arms 18 so as to raise or lower the valve member 17. The strip 9 is provided with a slit 20 so that when it is formed into a heater as is shown in Figure 1, the same will not buckle.

In use a strip of material is first cut out as is clearly illustrated in the drawings in Figure 2, the position of the various openings and cutout portions being governed by the type of motor to which the heater is to be used. The necessary bolts in the motor are removed and likewise the manifold is removed. The manifold branches are put through the openings 10 and connected to the motor again, and the bolts are inserted through the openings 11 and put into place. It will thus be seen that my device is firmly held into position, and cannot possibly become dislodged, until the bolts are removed. One of the features of this heater is the simple valve member 17 mounted at the rear end of my device. For instance, if it is in the summertime and it is not desired for the interior of the automobile body to be heated,

the valve member would be raised so as to close the opening at the end. It will thus be seen that the heated air will pass through the opening 15 down under the foot-board of the automobile. However, if it is desired to heat the interior of the car, the valve member will be put in a position as is clearly shown in the drawings, and the air will blow into the front end of my heater through my device, being heated by reason of the exhaust manifold, and will pass through the rear opening end of the device into the interior of the car, thereby warming the feet of the occupants. It will be seen that I have devised an efficient device, whereby the gasoline may be preheated so as to vaporize the same, and also have utilized the heat thrown off from the exhaust manifold, to warm the interior of an automobile.

26 It is to be understood that the form of my invention herewith shown and described, is to be taken as the preferred embodiment of the same, but that changes in details may be made providing the same do not depart from

the spirit of my invention or the scope of the subjoined claims.

Having thus described my invention, what I claim as new, and desire to secure by Letters Patent is:—

A heater for automobiles comprising a body formed of a single sheet of metal folded to provide a top wall and spaced depending inner and outer side walls of substantially the same size and shape to receive the branches of exhaust manifold of an internal combustion engine, the inner wall being provided with openings to receive the branches of the manifold, means for holding the body on the manifold, inwardly directed overlapping flanges formed on the side walls of the body at the rear end of the body, said side walls being provided with aligned openings and means cooperating with said openings for permitting the control of the flow of heat and air through said body. 40 45

In testimony whereof I affix my signature.

PALMER O. MELAAS.
